UNITED STATES PATENT OFFICE.

DORAH W. WILT, OF UNIVERSITY PLACE, NEBRASKA.

COMBINATION-LOCK.

1,118,252.

Specification of Letters Patent.

Patented Nov. 24, 1914.

Application filed October 23, 1911. Serial No. 656,095.

To all whom it may concern:

Be it known that I, DORAH W. WILT, a citizen of the United States, residing at University Place, in the county of Lancaster and State of Nebraska, have invented 5 a new and useful Combination-Lock, of which the following is a specification.

The present invention relates to improvements in combination locks, the primary 10 object of the invention being the provision of a combination or permutation lock, which dispenses with the employment of the usual manually operated bolt actuated mechanism, the knob actuated stem of the combination portion being provided with a slidably mounted bolt engaging arm or lever adapted to be controlled entirely by the tumblers of the lock to be projected into and out of bolt actuating position.

15 A further object of the present invention is the provision of a combination lock, which by reason of the fact that no manually operated bolt mechanism is employed and further that the dial and knob may be 20 rotated in either direction when the tumblers are in locked position without any strain being thrown upon the tumblers and other parts, this particular arrangement, rendering the lock less liable to be picked 25 by experts, and preventing any injury to the working parts due to usual method of forcing the tumblers by the manual bolt actuating lever when attacked by burglars.

30 A still further object of the present invention is the provision of a tumbler casing in which is mounted a plurality of disk tumblers, each of which is provided with a similarly shaped peripheral slot, while fitting exteriorly of all the tumbler disks and 35 having a rim extended to incase their peripheries is the main tumbler, which acts as a guard to prevent the pin of a slidably mounted arm or lever, which is disposed to be thrown into and out of engagement with 40 a bar for actuating the bolts, from entering the slots of the tumblers except when the pin is adjacent the slot of the main tumbler, the knob and dial device being connected to rotate the main tumbler so that 45 when rotated according to the proper combination its slot will be brought into alignment with all of the slots of the disk tumblers, when in an uppermost position, so that the gravity of the locking lever, or a 50 slight movement of the main tumbler will cause the pin carried by the lever to slide

downwardly into all of the slots and throw the lower end of the lever into the path to engage the bolt actuating bar, whereby the movement of the knob and dial in one direction will release the bolt, while the movement in the opposite direction will release the lever and cause it to be again locked out of bolt engaging position by the tumblers.

55 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

60 In the accompanying drawings:—Figure 1 is a front elevation of the lock as applied to a safe door. Fig. 2 is a rear elevation thereof. Fig. 3 is a rear elevation of the tumbler casing with the actuating lever or 65 arm in bolt throwing position. Fig. 4 is a section taken on line 4—4 of Fig. 1. Fig. 5 is a perspective view of the main tumbler *per se*. Fig. 6 is a perspective view of the actuating lever or arm *per se*. Fig. 7 is a 70 perspective view of the lever attaching end of the main stem. Fig. 8 is a plan view of one of the tumblers. Fig. 9 is a plan view of one of the tumbler separating washers.

75 Referring to the drawings, the numeral 1 designates the safe door, having mounted 80 therein and thereupon the dial casing or rim 2, the dial 3 carried by the knob 4, being so mounted that the threaded stem 6 of the knob will extend through the aperture 85 5 of the casing and door, and concentrically of the tumbler casing 7.

85 The threaded stem 6 as shown in Fig. 7, is provided with a longitudinal slot 8, the end 9 having two flat sides and the threaded concentric opening or socket 10, the locking screw 11, being mounted within the socket 10, while a key 18, enters the slot 8, for the purpose of properly securing the main tumbler 20 and its hub 19 to the stem. 90

95 Concentrically of the casing 7 is a sleeve 13, provided with a longitudinal slot 14, for the reception of the lugs 15 of the spacing washers 16, which are disposed between the respective tumblers or disks 17, which are 100 mounted, as is the usual practice with permutation locks, within the casing and carry

the usual studs or screws 17', whereby the slots 17" of the respective disks 17 may be alined, as shown in Fig. 4. As before stated the main tumbler 20 is keyed upon the inner 5 end of the stem 6, while fitting about the extreme end of the casing 7 and stem 6, is a cover disk 12.

The main tumbler 20 is provided with the rim 21 which extends to incase the peripheries of the tumbler 17, the tumbler 20 being 10 provided with cam edge 22 and with the opposed edge 23, both providing a slot to aline when the proper combination has been employed, with the slots 17" of the disks 15 or tumblers 17, so that the pin 32 of the bolt actuating lever or arm 29 will enter all of said slots, and thus permit the proper actuation of the lever or arm 29, as will presently appear. The rim of the tumbler casing 7 is provided with an aperture 24 at its 20 upper portion, one wall of which has projecting downwardly and within the casing 7, a lug 25, the opposed portion of the rim, or rather at a diametrically opposite point 25 to the aperture 24, is a recessed portion providing the two shoulders 27 and 28 in the rim of the casing 7. The tumbler 20 carries a screw or stud 20', to coact with the screws or studs 17' of the tumbler 17, thus providing 30 a coacting means, as is usual, between the tumblers, so that the slots 17" and the slot formed by the edges 22 and 23 in the tumbler 20 may be alined.

The locking actuating arm or lever 29, is 35 provided with a key-hole slot 30, to fit slidably upon the reduced portion 9 of the stem 7, between the outer face of the main tumbler 20 and the cover 12. This lever or arm 29, is further provided with the terminal 31, carrying a pin 32, which as above described is adapted to register with the slots of the tumblers and main tumbler when the proper combination has been worked, or to ride upon the periphery of the 40 rim 21 of the tumbler 20 when the slots of the tumblers are out of registration. The extreme end 33 of the terminal 31 when the lever is in the position as shown in dotted lines Fig. 2, abuts the inner wall of the casing 7 at 26, the arm 33' when in this position having engaged the pin 37 of the bar 38 and retracted the bar to unlocked position. A second arm 33 is carried by the lever 29, and this arm 33 is disposed for 45 movement within the slotted upper end of the pivoted lever 39, which when the device is used in connection with an automobile mechanism, controls the switch in the electrical circuit thereof, thus providing in a single lock a means for actuating the locking bar 38 and for operating the switch actuating lever 39.

Presupposing the parts to be in the position as indicated in full lines Fig. 2 and 50 dotted lines Fig. 3, the bar 38 being in

locked position and it is desired to release the bar. To accomplish this, that is to cause the arm or lever 29 to first assume the full line position as shown in Fig. 3 and finally the dotted lines, as shown in Fig. 2, the knob 4 is actuated to bring all of the slots 17" of the respective tumblers 17 and the recess formed by the cam edges 22 and 23 of the tumbler 20 into registration, at which time the pin 32 of the arm or lever 29, due 55 to the gravity of the lever 29, will enter said slots, as indicated in dotted lines Fig. 3 and in full lines Fig. 4. The knob 4 is now turned to the left, as viewed in Fig. 1 or to the right as viewed in Fig. 2, and as 60 the lever 29 has lowered to have the reduced portion 9 of the stem 6 fit in the reduced portion of the slot 30, the lever 29 is rotatable with the stem 6, so that the movement of the stem 6 will move the lever and 65 as the extreme end 33 of the arm or lever 29 has been retracted from the dotted line position Fig. 3, to the full line position, the outer end 33 of the lever 29 will be within the inner wall of the casing 7 and assumes 70 the position as indicated in dotted lines Fig. 2, this movement causing the arm 33' to pass between and to abut the pins 37 and move the locking bar 38 to the unlocked position. 75

To lock the bar 38, the knob 4 is moved 80 to the right as viewed in Fig. 1, or to the left as viewed in Figs. 2 and 3, and as the portion 9 is still within the reduced end of the slot 30, the end 33 of the arm or lever 29 is brought into engagement with the lug 85 25, and as the continued movement of the knob 4 rotates the tumbler 20, the cam edge 22 riding under the pin 32 elevates the lever 29, the reduced end 9 of the stem being a loose fit in the reduced portion of the key-hole slot 30, and permitting such movement. 90 As the knob 4 is still rotated, the lever 29 is elevated from the full line position, Fig. 3, to the dotted line position, at which time the pin 32 rides upon the periphery of the 95 tumbler 20, and the knob 4 is free to be rotated to throw the slots 17" of all tumblers tumblers mounted therein, a knob actuated stem concentric of the casing and tumblers and operably connected to the tumblers, a bar, an oscillatory lever of greater length than the diameter of the casing slidably mounted upon the stem and coacting means carried by one of the tumblers and the lever for imparting a sliding movement to the lever, the lever being locked against oscillatory movement when the tumblers are in locking position and being permitted an oscillatory movement when the tumblers are in unlocking position.

3. A combination lock, comprising a tumbler casing having an inner open end, the rim of which is provided with diametrically disposed reduced and enlarged recesses, a plurality of tumblers mounted in the casing, each of said tumblers having a peripheral slot, a knob actuated stem concentric of the casing and tumblers and operably connected with the tumblers, a double-armed lever slidably and pivotally mounted upon the inner end thereof, a bar, and co-acting means carried by one of the tumblers and lever for imparting sliding movement to the lever, whereby the lever is locked against oscillatory movement when the slots of the tumblers are out of registration or is permitted an oscillatory movement when the slots of the tumblers are in registration.

4. A combination lock, comprising a tumbler casing, a plurality of tumblers mounted therein and provided each with a slot opening toward the periphery, a knob actuated stem concentric of the casing, a main tumbler carried by the stem and in co-operative relation to the other tumblers, said main tumbler being provided with a slot having a cam-shaped wall, said casing being provided with diametrically disposed recesses, a lever mounted intermediate of its ends upon the stem and slidably thereupon, said lever being of a greater length than the diameter of the casing, a bar, a pin carried by the lever disposed for movement into and out of registration with the slots of all of the tumblers, said lever when in registration with the slots being disposed to engage the bar to actuate the same when the stem is rotated in one direction, a reverse rotation of the stem due to the cam shaped wall of

the slot of the main tumbler when in engagement with the pin of the lever moving the lever out of the path to engage the bar and locking the lever against sliding movement.

5. A permutation lock comprising a turning dial having a stem provided with an inner end having flat sides, a plurality of permutation disks supported by said stem and having notches adapted to be brought into registration with each other, means on the respective disks for causing successive rotation thereof, a displaceable lever supported upon the stem and having a key-hole shaped slot therein, whereby on the movement of the lever in one direction it will lock with the stem and on movement thereof in the opposite direction it will disengage from the stem, means carried by the lever and engageable in the notches in the disks when the lever is in locked engagement with the stem, and a trip latch operated by said lever.

6. A permutation lock comprising a turning dial having a stem provided with an inner end having flat sides, a plurality of permutation disks supported by said stem and having notches adapted to be brought into registration with each other, means on the respective disks for causing successive rotation thereof, a displaceable lever supported upon the stem and having a key-hole shaped slot therein, whereby on the movement of the lever in one direction it will lock the stem and on movement thereof in the opposite direction it will disengage from the stem, a locking lip formed on the lever and engageable in the notches in the disks when the lever is in locked engagement with the stem, a trip latch operated upon by the lever and movable into and out of the path of an element for the locking and unlocking thereof, and a stationary means surrounding the disks and adapted to act upon the lever for holding the lip thereof engaged in the notches in the disks when the said lever is in one position.

In testimony that I claim the foregoing as my own, I have hereto affixed my signature in the presence of two witnesses.

DORAH W. WILT.
